[57] CLAIM

The ornamental design for a detachable handle for adjustable medical light or the like, as shown and described.

DESCRIPTION

FIG. 1 is a top, front, left side isometric view of a detachable handle for adjustable medical light or the like showing our new design;

FIG. 2 is a left side elevational view thereof on an enlarged scale, the right side being identical;

FIG. 3 is a front elevational view thereof, the rear being identical;

FIG. 4 is a top plan view thereof;

FIG. 5 is a bottom plan view thereof;

FIG. 6 is a top, front, left side isometric view of a second embodiment of our new design;

FIG. 7 is a left side elevational view thereof on an enlarged scale, the right side being identical;

FIG. 8 is a front elevational view thereof, the rear being identical;

FIG. 9 is a top plan view thereof;

FIG. 10 is a bottom plan view thereof.

The broken lines are shown for illustrative purposes only.
